[57] CLAIM

The ornamental design for a food mold, as shown and described.

DESCRIPTION

FIG. 1 is a rear perspective view of a food mold showing my new design;

FIG. 2 is a left side elevational view thereof, the oposite side being a mirror image;

FIG 3 is a top plan view thereof;

FIG. 4 is a bottom plan view thereof;

FIG. 5 is a front elevational view thereof;

FIG. 6 is a rear perspective view of an alternate embodiment of FIG. 1;

FIG. 7 is a left side elevational view of FIG. 6, the opposite side being a mirror image;

FIG. 8 is a top plan view of FIG. 6;

FIG. 9 is a bottom plan view of FIG. 6; and,

FIG. 10 is a front elevational view thereof.

The handle in FIGS. 7-9 is shown broken away for ease of illustration.
